PRINTING MACHINE

Walter T. Gollwitzer, Chicago, Ill., assignor to
Addressograph Company, Wilmington, Del., a
corporation of Delaware

Application January 28, 1931, Serial No. 511,670

32 Claims. (Cl. 101—47)

This invention relates to printing machines in which printing impressions are made from printing devices sequentially passed therethrough.

Printing devices of the kind employed in my machine are usually filed in the drawers of suitable cabinets in a determined sequence and when impressions are to be made therefrom these printing devices are introduced into a magazine in the machine and from which they are withdrawn and sequentially passed through the machine. Frequently it is desirable not to make impressions from all of the printing devices passed through the machine and it is therefore the salient object of my invention to provide a novel printing machine wherein only determined or selected of the printing devices will be used in a printing operation.

In order to classify the printing devices to afford selection lacuna or other identifying means are provided thereon and another object is to provide a machine wherein a novel detector is provided, engageable with the lacuna or identifying means to determine the operation of the machine.

The devices performing the selection, or as they are known selecting devices, usually function to control operation of the printing member or platen but another object herein is to provide a selecting novel device which may be used to control other mechanisms in the machine.

It is especially desirable that the set-up of the detecting portions be accurately determined in order that impressions will be made only from the printing devices from which such impressions are desired, and it is therefore a further object to provide a novel selecting device which may be accurately set up to select only determined printing devices and to provide a removable member or matrix whereby the set-up of the machine may be varied.

Further objects are to provide a printing machine wherein the selection set-up may be expeditiously brought about; wherein the selection set-up may be easily reversed, that is, when printing devices are once passed through the machine certain of the printing devices will be printed or will be, as it is termed, skipped and in my improved device this may be reversed so that if the printing devices are again passed through the machine the devices which were skipped on the first sequential passage will be used in a printing operation in the second passage whereas those printed on the first passage through the machine will be skipped on the next passage; wherein the detector of the selector

is moved into detecting position in positive synchronism with the printing device feeding movement; wherein a signal device may be provided which will be rendered operative under certain conditions of operation; and wherein the member controlling the operation will be held in a normal position until actuated by the selecting mechanism.

In the selected embodiment of the invention illustrated in the accompanying drawings,

Fig. 1 is a fragmentary transverse sectional view of a typical printing machine with which my invention may be associated;

Fig. 2 is another transverse sectional view across the machine taken at a point forwardly 15 of the section of Fig. 1;

Fig. 3 is a transverse view of the machine illustrating portions of my improved selecting mechanism;

Fig. 3a is an elevational view of the removable 20 part of the selecting mechanism;

Figs. 3b and 3c are sectional views of the part illustrated in Fig. 3a showing modifications of the arrangement thereof;

Fig. 4 is a sectional view taken transversely 25 of the printing device guideway in the machine just forwardly of the detecting portions of the selecting mechanism;

Fig. 5 is a sectional view taken substantially on the line 5—5 on Fig. 4;

Fig. 5a is a diagrammatic view illustrating the different positions into which the member positioned by the selector may move under different conditions of operation;

Figs. 6, 7, 8 and 9 are sectional views substantially similar to Fig. 5, illustrating different operative positions of the detecting portions of my improved selecting mechanism;

Fig. 10 is a longitudinal sectional view through the printing device guideway;

Fig. 11 is a view of a cam mounted on one of the driving shafts of the machine and operating a part of the device shown in Fig. 10; and

Fig. 12 is a sectional detail view illustrating operating means for other of the devices shown in 45 Fig. 10.

In the accompanying drawings illustrating a selected embodiment of my invention, I have shown, for the purpose of illustration, a portion of a printing machine of the kind disclosed in the 50 application of Edwin C. Colyer, Serial No. 506,553, filed January 5, 1931, and this machine includes a table top 103 on which the printing impressions are performed. The machine also includes castings extending transversely of the machine and 55

one of these castings, indicated by 23 (Fig. 1), is illustrated in the accompanying drawings, and these castings provide bearings in which the main drive shaft 37 is journaled. Fast on this 5 main drive shaft 37 is a track cam 83. Journaled in the casting 23 and in a similar casting juxtaposed thereto is a shaft 77 and fixed thereon is the bearing portion 78 of the platen arm 79. Freely mounted on the shaft 77 is a rocker 80 including 10 an arm carrying a roller 82 disposed in the track of the cam 83. Provided on the rocker 80 is a ledge 81 and cooperating therewith is a ledge 84 unitary with a member fast on the shaft 77. Thus, when the parts are disposed in the position 15 illustrated in Fig. 1, the ledge 81 engages the ledge 84 and acts through the shaft 77 to hold the arm 79 in the upper position illustrated. The platen arm supports an arm 87 carrying platen head embodying tracks 98 on which rollers in the 20 bracket 97 travel, this bracket carrying the platen P which makes impressions from printing devices, positioned therebelow, through a suitable ink ribbon. The arm 99 of the bracket 97 is pivotally connected to an arm 100 mounted on a shaft 104. A spring 101 extends between the 25 presser foot 102, carried on the arm 87, and the arm 100 and serves to hold the platen P in a forward position. The platen P is moved rearwardly to make a printing impression by movement imparted to the arm 105 fast on the shaft 104 in a manner described in the previously referred to application. When the track cam 83 moves the roller 82 from the position shown the ledge 81 is moved from engagement with the ledge 30 84 and therefore the platen 79 may pivot in a counter-clockwise direction to thereby move the platen P toward the table top 103 whereby an impression may be made thereby from a printing device moved into position therebelow. When 35 the platen arm 79 moves in the counter-clockwise direction the hook portion 89 on the bell crank 88 pivotally mounted on an arm fixed to the rock shaft 77 disengages the stop 90, and the shoulder 92 on the bell crank is urged into position to be 40 engaged by the abutment 95 on the rocker 80 by the spring 91, and when the shoulder 92 is engaged by the abutment 95 printing impetus is imparted to the platen. Simultaneously with this imparting of printing impetus to the platen 45 the arm 105 is motivated to move the platen P against the action of the spring 100 to perform a printing operation from the printing device positioned therebelow.

Printing devices are moved into printing position along printing device guideways provided in the castings 131 and 132 (Fig. 4) disposed substantially medially of the machine and extended parallel to the castings similar to the casting 23. The means for moving the printing devices, which 55 are indicated by D, into position below the platen include carrying bars 136 which are movable in substantially rectangular orbits. In order to hold the printing devices in position during certain portions of the movement of the carrying 60 bars, locking bars 137 are provided which are movable vertically. The manner in which the carrying and locking bars are supported in position and the manner in which movement is imparted thereto is clearly described in the referred 65 to application. At spaced intervals in the upper edges of the carrying bars 136 are recesses 144 (Fig. 5) and similar recesses 145 are provided in the upper edges of the locking bars 137 and the printing devices D are embraced in these 70 recesses. The carrying bars impart a step by step

movement to the printing devices and printing impressions are taken therefrom during at rest periods in this step by step movement and the operation of the selecting mechanism forming the subject matter of this invention occurs during a similar period.

The manner in which the carrying bars and locking bars are operated is illustrated in Figs. 10 to 12, inclusive. Assuming the carrying bars to be in the position illustrated in Fig. 10, movement is imparted thereto as follows: The carrying bars will first move forwardly in a horizontal plane, then downwardly, rearwardly and then upwardly back into the position illustrated in Fig. 10, and it is this rectangular movement of the carrying bars 10 that imparts the step by step movement to the printing devices. The locking bars merely move vertically to engage and disengage the printing devices during certain phases of the rectilinear movement of the carrying bars. In order to impart up and down movement to the locking bars and rectangular movement to the carrying bars I provide cam bars below the locking bars and carrying bars respectively. Cam bars, such as 138, are positioned below the locking bars 137 and mounted on the ends thereof on the sides disposed toward the carrying bars are blocks and arranged between these blocks and below ledges on the castings, such as 131, are cam bars 142 and the manner in which these cam bars 142 are mounted 30 is such that these bars are movable horizontally with the cam bars 138. Rollers 140 are mounted on the castings, such as 131, and in the cam bars 138 are cam grooves 139 and in the cam bars 142 are cam grooves 143. The cam grooves in these 35 cam bars are adapted for cooperation with the rollers 140.

At the beginning of an operation as shown in Fig. 10, the cam bars are so disposed that the rollers engage dwells in the cam grooves 139 and these rollers also engage the lower edges of the cam bars 142 adjacent the cam grooves 143. Therefore, the locking bars 137 are disposed in a lower position and the carrying bars 136 are held in an upper position. The recesses 145 in the 40 locking bars are arranged at the dwell positions of the printing devices in their step by step movement along the printing device guideway. When the parts are in the position illustrated in Fig. 10, the most rearward of the notches 144 in the 45 carrying bars are disposed below the lower end of the magazine M and when the carrying bars are moved forwardly the upper surfaces of the rear ends of said carrying bars move into position below the magazine to prevent the printing devices therein from moving therefrom. The lowermost of the printing devices in the magazine M move into the rearwardmost of the recesses 144 when these recesses are disposed below the magazine and when the carrying bars move forwardly the printing device in this recess is moved forwardly into the dwell position first removed from the magazine M. Movement is imparted to the carrying bars in the following manner:

A gear 117 is fast on the shaft 62 and this gear is of the intermittent type, that is to say, it is provided with sets of teeth 118 and 119 intermediate of which there are pitch line dwells 120 and 121. A stub shaft 122 is mounted in the frame of the machine and fast thereon is an intermittent gear 123 having sets of teeth 124 and 125 intermediate of which there are pitch line dwells 126 and 127. When the shaft 62 is rotated in a clockwise direction, as viewed in Fig. 12, the teeth 118 engage the teeth 125 and rotate the gear 70 75

123 and consequently the shaft 122 until the dwell 120 engages the dwell 127 whereupon no further movement is imparted to the gear 123 until the teeth 119 engage the teeth 124 at which time the gear 123 will be rotated substantially one-half revolution. It is therefore manifest that an intermittent motion is imparted to the shaft 122 for when the sets of teeth are engaging, the shaft 122 rotates but this shaft remains stationary when the pitch line dwells are in engagement. A crank 127 is fast on the shaft 122 and a link 128 is pivotally connected to this crank and also to a rocker 130 fast on a shaft 133 carried by the frame. Also fast on the shaft 133 are rockers 134 and links 135 interconnect the rockers 134 and the rear ends of the carrying bars 136.

When the shaft 122 is operated the crank 127 transmits movement through the link 128 to the rocker 130 and this movement is transmitted through the shaft 133, rockers 134 and links 135 to the carrying bars 136 and at the initiation of the operation the carrying bars 136 are moved sufficiently to position the rearwardmost recess 144 above the rearwardmost recess 145 and when 25 the carrying bars have attained this position the locking bars are operated.

This is brought about by the track cam 150 fast on the shaft 62. A roller 149 carried by an arm 148 fast on the shaft 147 journaled in castings, 30 like the casting 131, is positioned in the track of the cam 150. Rockers 146 having bifurcations 151 in the upper ends thereof are fast on the shaft 147. Rollers 152 mounted on the cam bars 138 are disposed in the bifurcations 151 and when the 35 shaft 147 is actuated by the cam 150, the rockers 146 move forwardly whereupon the tapered portions of the cam grooves 139 engage the rollers 140 and cause the cam bars 138 and the locking bars 137 that rest thereon to move upwardly and 40 when this occurs the printing device which has been picked up by the rearwardmost recess 144 is engaged in the rearwardmost recess 145.

The tapered portions of the cam grooves 143 are so disposed that as soon as the cam bars 138 have moved upwardly to correspondingly move the locking bars 137 the tapered surfaces thereof will move into alignment with the rollers 140 and continued forward movement of the cam bars as caused by the rockers 146 will cause the 45 rollers 140 to enter the cam grooves 143 whereupon the cam bars 142 are lowered which causes a corresponding lowering of the carrying bars 136. Immediately after this lowering of the carrying bars 136 the shaft 122 will again be 50 actuated for during the lowering movement the dwells on the gear 117 and the pinion 123 have been in engagement and the shaft 122 will not have been turning. But now the shaft 133 will be motivated to move the rockers 134 rearwardly 55 and after the rockers have moved back into the position shown in Fig. 10 the cam 150 will again actuate the shaft 147 to move the rockers 146 rearwardly. Now the above described movements will be reversed, that is, first the carrying bars 136 will be moved upwardly and after the carrying bars have moved upwardly so that the printing devices are again engaged in the recesses 144 the locking bars 137 will move downwardly to disengage the recesses 145 from the printing devices. 60

70 The printing device which was moved forwardly on the previous operation of the carrying bars will be engaged in the penultimate of the recesses 144 while the lowermost of the printing devices in the magazine will be in the rearwardmost of the recesses. Thus when the above described opera-

tions are repeated the first released printing device will be moved into alignment with the penultimate recess 145 and the above described operation will be repeated and in this instance the locking bars 137 engage and retain two printing devices. When the above described operations are again repeated the locking bars engage three printing devices and the forwardmost of these printing devices will be disposed in selecting position for cooperation with the selector mechanism forming the subject matter of this invention.

This selector mechanism in one of the forms described herein cooperates with the printing device in selecting position and determines how the platen P will operate on the next operation 15 of the machine, that is to say, whether or not an impression will be made from this printing device now in selecting position for this printing device will be moved into printing position below the platen P and onto the anvil A in the next opera- 20

25 As stated, the selecting mechanism is positioned to act on the printing device immediately behind the printing device disposed at printing position in the machine and from which the platen P may make an impression and the selecting mechanism acts to determine the operation of the printing mechanisms when this printing device moves into printing position. The lacuna or identifying means provided on the printing devices in the present instance may be in the form of removable tabs of the character disclosed in the Duncan Patent No. 1,082,505, patented December 13, 1913. As shown in that patent the printing devices are arranged to retain twelve 30 tabs thereon and each of these tabs may have sections thereof cut away and by so doing the number of lacuna or identifying means may be doubled and thus I am able to provide twenty-four lacuna or identifying means or, as it is known, selecting positions. Each of the twenty-four positions provide what is known as a primary selection and by arranging the detecting means 35 for group operation so that two or more of these primary selections will need cooperate to bring about a desired result I may accomplish what are known as secondary selections. Since I have provided twenty-four selecting positions, I have also provided twenty-four detecting members and while I have shown such an arrangement it is to 40 be understood that a greater or less number of these positions and detectors might be provided without departing from the purview of the invention.

In the illustrated embodiment of the invention 55 I provide a block 10 supported by a bracket 11 including pads 12 secured to the locking bars 137 by screws 13 or the like. The detecting members or feeling fingers 14 are mounted in slots in this block, these fingers including detecting portions 15 adjacent which there are slots 16 and in the forwardly disposed portion of the fingers are slots 17. Pins 18 and 19 extend across the block 10 through the slots therein and the fingers are so arranged in the slots in the block 60 that the slots 17 therein embrace the pin 19 while the slots 16 embrace the pin 18. Leaf springs 23 are arranged in a recess in the block 10 and act on the under side of the fingers 14 to urge the same upwardly, said fingers pivoting about the pin 19 and upward movement thereof being limited by the pin 18. The fingers 14 include tail portions 21 which extend rearwardly beyond the rear edge of the block 10. The detecting portions 15 of the fingers 14 are vertically aligned 65

with the lacuna L on the printing device in selecting position, illustrated in Fig. 5.

It has been pointed out that the locking bars 137 are movable vertically and when a printing device moves into selecting position these locking bars are in lower position. However, as soon as the printing device is disposed in selecting position, the locking bars move upwardly and since the block 10 is carried by the bracket 11 that is secured to these locking bars, this block consequently moves upwardly and the detecting portions on the fingers cooperate with the lacuna on the printing devices. It has been pointed out that the lacuna in the present instance are in the form of tabs which may have sections thereof cut away. Thus, when the feeler fingers move upwardly the portions thereof engaging the tabs will be held against further movement and these fingers will be pivoted about the pin 19 to assume positions substantially like that shown in broken lines in Fig. 5. The detecting portions of the fingers not engaging tabs due to the absence of a tab or a cut away portion thereof will not be pivoted and should no tabs be provided on the printing device, or if the aligned portion of the tab is cut away, the detecting fingers will move past the printing device without being pivoted about the pin 19 and will be disposed in positions substantially like that shown in full lines in Fig. 5. To prevent upward movement of the lacuna and the printing devices when engaged by the fingers a strip 22 is secured to and extends between the upper edges of the castings 131 and 132 above the position of the fingers 14. This strip includes a depending portion in the lower surface of which a plurality of slots are provided, which slots are aligned with the fingers 14, and the fingers 14 move into these slots when there are no tabs on the printing device in selecting position or when portions of the tabs are cut away.

It has been pointed out that the fingers 14 may be pivoted about the pin 19 and that under certain conditions of operation certain of the fingers will be pivoted while others will not be pivoted and therefore the tail portions 21 of the fingers may be disposed in different horizontal planes depending upon this pivoting or the lack of it. The positioning of these tail portions is utilized to determine the selection, and this is brought about in the following manner: The bracket 11 includes arms 25 in which a shaft 26 is journaled. On this shaft 26 an arm 27 is pivotally mounted and which includes a head 28. In the forwardly disposed face of this head are two transversely extending grooves 29 and 30 and at the side edges of the head vertically extending grooves are provided, and the face of the head is recessed in alignment with these grooves. Therefore, a removable member 31 may be extended into these grooves to be disposed on the forward face of the head 28. This removable member 31, known as a matrix, is illustrated in Fig. 3a and includes a grip portion 32. Adjacent the upper portion of the matrix 31 provision is made for two transverse rows of openings, the openings in the respective rows being aligned with each other. When the matrix is arranged on the head 28 these rows of openings are respectively aligned with the grooves 29 and 30. The openings in the rows or the lack of them determines the selection. The number of openings in each row corresponds with the number of fingers 14 and the openings are positioned to be respectively aligned with the fingers when the matrix is mounted on the head 28. The open-

ings in the upper row are intended to cooperate with the groove 29 and the tail portions 21 of fingers which are not pivoted about the pin 19 while the openings in the lower row are intended to cooperate with the groove 30 and the tail portions of the fingers pivoted about the pin. At opposite ends of the head 28 lugs 33 are provided in which a pin 34 is supported which therefore extends across the front of the head 28 forwardly of the matrix 31. This pin is so disposed that it extends between the openings 35 of the uppermost row of openings in the matrix and the openings 36 in the lowermost row of openings therein, and the purpose of this pin is to insure the proper disposition and guiding of the tail portions 21. The head 28 is urged toward the fingers 14 by spring 37 and is movable against the action of this spring in a manner to be described.

The arm 38 is provided which may either be pivoted on the shaft 26 or at a point on either side thereof and in this manner the selecting mechanism may be arranged to operate on printing devices of different widths. In the disclosed embodiment of the invention, the arm 38 is pivoted on a shaft 39 disposed forwardly of the shaft 26 and this illustrated embodiment is that which operates on printing devices of an intermediate width. Pivotally mounted on the shaft 26 is a casting 38' which has a portion thereon that is interfitted with a bifurcated portion on the arm 38 to thereby interconnect the arm 38 and the casting 38', this interconnection being indicated at 39' (Fig. 6). A depending lobe 40' on the casting 38' has an adjusting screw 41 mounted therein against which a pin 42' connected to the arm 38 bears and this pin is held in this position by the spring 43' extended between the arm 38 and the casting 38'. Therefore this arm and this casting are connected to act as a unit. Carried by the casting 38' is a set screw 41 including a tip 42 extendable into an opening such as 43 (Fig. 3a) in the matrix. Provision is made whereby the opening 43 may be located in either of two locations respectively illustrated by full and dotted lines in Fig. 3a and the purpose of this will be described. A spring 40 acts on the arm 38 and therefore the casting 38' and urges the set screw 41 toward the matrix to maintain the tip 42 in the opening 43. The casting 38' includes a handle 44 and a handle 45 is provided on the head 28. By gripping these handles the head 28 may be pivoted to disengage the tip 42 from the opening 43 and therefore the matrix may be slid from the head 28 and when these handles are released, the springs acting on the members reposition them in the illustrated position and the tip 42 again enters the opening 43 in the newly inserted matrix to thereby prevent displacement thereof.

Both the block 10 and the head 28 move upwardly when the locking bars 137 move upwardly and the spring 37' normally urges the head 28 toward the tail portions 21. Therefore in order to permit positioning of the tail portions in accordance with the lacuna it is necessary that the head 28 be moved against the action of the spring 37' to disengage it from the tail portions and this is brought about by the rod 46, one end of which is engageable with the depending portion 47 of the arm 27. The rod 46 has an adjustable portion 48 and extends along the casting 131 and includes an end portion engageable with one end of a rocker 49 pivotally mounted at 50 on the casting 131. In the manner described the shaft 62 operates the printing device feeding

mechanism and the locking bars 137. Thus, by providing a cam 51 on the shaft 62 engageable by a roller 52 on the arm 49 the rocker may be actuated in timed relation with the operation of the locking bars. Fast on the shaft 62 is a pinion 62' meshed with a gear 37 mounted on the drive shaft 37 and rotated thereby, and these gears are of a predetermined ratio whereby the shaft 62 operates in timed relation with the drive shaft 37 when said drive shaft is set in operation. Thus, each time the locking bars are moved upwardly the rod 46 will be moved and the movement of this rod causes the head 28 to move away from the tail portions 21, to be disposed in the position illustrated in Fig. 6, and therefore when the fingers 14 are first engaged with the lacuna, to be positioned in accordance therewith and be disposed above and below the pin 34, said pin and the head 28 will be retracted away from said tail portions. After the tail portions are positioned by cooperation with the lacuna or other identifying means the roller 52 moves onto a drop in the cam 51 and the rod 46 will therefore be moved rearwardly due to the action of the spring 37' and the head 28 will again move toward the tail portions 21 whereupon the pin 34 moves into cooperation with the tail portions 21 and thereafter the pin 34 holds the tail portions 21 above or below the pin depending upon the position in which they have been disposed by the cooperation of the fingers 14 with the lacuna L or other identifying means and the head 28 will be positioned in accordance with the cooperation of the tail portions 21 with the openings or the lack of openings 35 and 36 in the matrix 31.

When the selecting mechanism is set, for example, to print from printing devices not having lacuna thereon in a definite position, it may be accomplished by utilizing a cut away portion of a tab. Thus, the detecting portion of the finger cooperating therewith will not be pivoted when the fingers are moved upwardly and this tail portion will be disposed above the pin 34. Under this condition all of the openings 35 would be formed save the one aligned with this finger. Therefore when the head 28 is moved by the spring 37' toward the tail portions 21 after the tail portions have been set and if the lacuna, is in accordance with the determined and desired selection this tail portion is above the pin 34 and therefore engages the face of the matrix since there is no opening at this point. All of the openings 36 would be formed. Thus, if the lacuna were not of the determined character the particular finger 14 would be pivoted to position the tail portion 21 below the pin 34 and therefore when the head 28 moved forwardly this tail portion would pass through the opening 36 in alignment with the closed opening 35, and this tail portion would therefore be extended into the groove 30. Manifestly, under this condition the head 28 would move forwardly in a greater amount than when the tail portion rested on the face of the matrix. It is therefore apparent that any desired selection may be brought about merely by determining which of the openings in the matrix are to be opened and which are to be closed and thus when the determined lacuna are on a printing device in selecting position the head 28 will be positioned in a certain position but when the determined lacuna are not on the printing device in selecting position the head 28 will be located in a different position. This different positioning of the head 28 is utilized to control the machine.

It has been pointed out that the arm 38 and

the casting 38' act as a unit and that the screw 41 bears against the head 28. Therefore when the head 28 is located in different positions the arm 38 is located in different positions. At the lower end of the arm 38 there is a plate 53 and the positioning of this plate serves to control the machine.

It has been previously described that the cam 83 acts to withdraw the ledge 81 from the ledge 84 to thereby permit the arm 79 to pivot and this ledge 81 is withdrawn on every operation of the cam 83 which is in every cycle of operation of the machine since the cam is fast on the drive shaft 37 which makes one revolution for each operation of the machine. Thus to prevent the platen arm from moving downwardly and making an impression from a printing device, which the selector has determined should be skipped, there is formed in the bearing portion 78 a notch 245 (Fig. 1) engageable by a hook 246 on the bell crank 247 fast on the shaft 248.

Fast on the shaft 248' (Fig. 2) is an arm 54 acted on by a spring 55 to be held in an upper position. On this arm 54 are plates 56, 57 and 58, the plates 56 and 58 being provided on one side of the arm while the plate 57 is on the other side, and the purpose of this arrangement will be set forth presently. These plates are notched in their upper edge for cooperation with the pointed end on the plate 53. On the shaft 248' is a rocker 226 carrying a spring-urged plunger 225 engageable with the arm 224 of the bell crank 218 fast on the shaft 248. When the arm 54 is moved against the action of spring 55 the plunger 225 moves arm 224 and shaft 248 to engage hook 246 with the notch 245, said hook normally being disengaged from said notch, as shown in Fig. 1.

In the arrangement of the invention shown in Fig. 7, the matrix is one wherein a printing operation is to be performed when the tail portions 21 move through openings therein into the grooves 29 and 30, and when a printing device having other than the determined lacuna thereon moves into printing position the head 28 and plate 53 are positioned as shown in full lines in Fig. 7. It will be noted that in the arrangement shown in Fig. 7 the locking bars 137 and consequently the fingers are in an upper position. However, when the locking bars move downwardly to permit the printing device in selecting position to be moved into printing position the fingers and associated parts are moved downwardly but when they are set in the position shown in full lines in Fig. 7 the plate 53 moves in such a manner that it does not engage any of the plates on the arm 54 and consequently this arm is not moved. Therefore, when the ledge 81 is moved away from the ledge 84 the arm 79 pivots and a printing operation is performed since the hook 246 does not engage the notch 245.

However, should a printing device move into position such that a tail portion 21 is prevented from moving through the matrix and merely engages the face of the matrix, as shown in Fig. 8, the plate 53 is positioned in alignment with the plate 51 and when the parts move downwardly the pointed end of the plate 53 seats on the notched upper end of the plate 57 and the arm 54 is pivoted which engages the hook 246 with the notch 245. Therefore, when the ledge 81 is moved away from the ledge 84 the arm 79 does not pivot and a printing operation is not performed. The foregoing is but an exemplary operation of my device and it is to be understood that the device might be arranged in another manner without de-

parting from the purview of my invention and the foregoing selection is merely one of a very large number which may be performed.

It may be desirable under certain conditions 5 to reverse the foregoing operation, that is, to print from printing devices which were skipped on the previously described sequential passage while those printing devices which were printed in this first passage are skipped. To this end 10 the device is arranged to be reversible. In the operation above described the plate 53 cooperated with the plate 57 which, as has been stated, is positioned on one side of the arm 54. It is therefore manifest that the arm 38 was aligned with 15 the plate 57 and under this condition of operation the tip 42 was disposed in an opening 43 in the matrix similar to that shown in dotted lines in Fig. 3a. When the operation is to be reversed the tip 42 is disposed in an opening 43 located 20 similarly to that shown in full lines in Fig. 3a. When this is done the arms 38 and the plate 53 are aligned with the plates 56 and 58 to cooperate therewith. The plate 58 is so positioned that when the tail portions 21 pass into grooves 29 and 25 30, the plate 53 seats in the notch at the upper end of the plate 58 and therefore the arm 54 is moved and when the tail portions do not enter these grooves, but engage the face of the matrix, the plate 53 is so positioned that it does not engage the plate 58. Clearly this is a reversal of 35 the previously described operation and therefore the manner in which the printing operations are performed from the printing devices is reversed. In order to insure that a matrix will only bring about a certain selection it is customary to provide but one of the openings 43 in each matrix. Thus, when it is desired to reverse the operation 40 in the above described manner two matrices are provided and with regard to the openings 35 and 36 these matrices are identical but in one the opening 43 is disposed in the full-line position in Fig. 3a while in the other the opening 43 is disposed in the dotted-line position in Fig. 3a. It is essential that the tip 42 enter one or the 45 other of the openings. Therefore, when a matrix is installed in position the desired selection is brought about for if the opening is not properly positioned the set-up cannot be completed. This would not be insured if two openings 43 were provided in each matrix. And it is for this reason 50 that two matrices of identical structure are provided with openings 43 located in different positions.

Sometimes it is desirable that a special selection 55 be made or that a certain condition be indicated such as the end of one series of printing devices and the beginning of another. Further, under certain conditions selections may be made but it is desirable that the operator be informed of 60 certain conditions or operations. An example of this would be in the use of addressing periodical publications for which purpose the address plates have lacuna thereon indicating the end of the period of the subscription and when one of these 65 printing devices moves into printing position it is desirable that the operator of the machine be advised of the fact in order that the printing device may be removed from the series. To this end I provide a signal device which in the present 70 instance is a bell, and this bell is rendered operative by providing on the matrix what are known as bell plugs. It may, for example, be desirable to ring the bell when an impression is made from the selected printing device and under other 75 conditions it may be desirable to ring the bell

when the impression is not made from the selected printing device.

To obtain this special selection I provide plugs of different heights and such plugs are illustrated in Figs. 3b, 3c and 9. Such a plug is inserted into either an opening 35 or an opening 36 depending upon the selection desired. In Fig. 3c what I call a short bell plug, indicated by 59, is provided, the extent of which above the face of the matrix is indicated by dotted lines in Fig. 10 9. In Fig. 3b a long bell plug is illustrated which is shown in Fig. 9 in full lines.

When the tip 42 is disposed in an opening 43 located at the full-line position of Fig. 3a, a short bell plug brings about a skipping operation while 15 a long bell plug brings about a printing operation. In Fig. 5a the various positions into which the plate 53 is movable are diagrammatically illustrated and the position of the plate 58 is indicated by M and, as has been described, 20 when the tail portions 21 pass into the grooves 29 and 30, when the plate 53 is aligned with plates 56 and 58, the plate 53 engages the plate 58, that is to say, it is disposed in the position M of Fig. 5a. But when the tail portions 21 engage 25 the face of the matrix, the plate 53 does not engage the plate 58 but rather is positioned in the position N of Fig. 5a. When the plate 53 is in the position M, the printing device determining the set-up of the selector is skipped, as has been 30 described, but when the plate 53 is in the position N, an impression is made from the printing device determining the set-up of the selector. The reason the plate 53 assumes the positions M or N is that the movable parts of the selector 35 pivot in different amounts depending upon the positioning of the tail portions 21 and when the tail portions 21 engage the face of the matrix, the plate 53 is positioned forwardly of the position in which it is disposed when the tail portions pass 40 through the openings in the matrix. Thus, if a protuberance is provided on the face of the matrix in the nature of say a short bell plug, the plate 53 is positioned forwardly of the position N, for a tail portion 21 engages this raised plug and 45 positions the plate 53 forwardly of the position N, as indicated by the position R in Fig. 5a, and when in this position the plate 53 is aligned with the plate 56 and the printing device which determined the set-up of the selector is skipped. As 50 shown in Figs. 5 to 9, inclusive, a member including a foot member 61 is connected to the plate 53 and the foot portion extends parallel to the plate 53 but is spaced from said plate to the rear thereof. As best shown in Fig. 8, when the plate 53 cooperates with either the plate 51 or the plate 58, the foot member 61 is spaced from the plate 66, which will be described more fully hereinafter. But when the plate 53 is moved into alignment with the plate 56, then the foot member 61 is aligned with the plate 66. Thus, when 55 the plate 53 is in the position R, the foot member 61 is aligned with the plate 66 and when a printing device is skipped, the foot member 61 operates the device to which the plate 66 is connected to operate a signal. Now should a tail portion engage a long bell plug, the plate 53 is 60 disposed forwardly of the position R and in the position S of Fig. 5a. When the plate 53 is in the position S of Fig. 5a, the foot member 61 is still 65 aligned with the plate 66. Hence, when the locking bars 137 move downwardly, the foot member 61 engages said plate 66 and even though a printing operation is performed, the signal is 70 operated. When the tip 42 is disposed in an 75

opening 43 located in the dotted-line position of Fig. 3a, the plate 53 is aligned with the plate 57. Under these conditions, when the tail portions 21 move through the openings in the matrix, the plate 53 moves into the position T of Fig. 5a and does not strike the plate 57 and consequently the device holding the platen against movement is not rendered operative and hence an impression is made from this printing device. When, however, the tail portions 21 engage the face of the matrix, the plate 53 moves into the position V of Fig. 5a and engages the plate 57 and the printing device determining this set-up of the selector is skipped. Now when a short bell plug 15 is provided and a tail portion 21 engages therewith, the plate 53 moves into the position W of Fig. 5a and as the plate 53 does not motivate the devices which hold the platen against a printing operation, an impression is made from the printing device determining the set-up of the selector. However, the position W is aligned with the position R and the foot member 61 engages the plate 66 and operates the signal. Thus, under these conditions of operation, a short bell plug indicates the printing of a printing device by operating the signal in contra-distinction to the other set-up of the device wherein the operation brought about by a short bell plug causes skipping of the printing device and the operation of the signal. In the disclosed embodiment of the invention, the machine is arranged so that the audible signal is operated when the plate 53 is in the position W and under these conditions an impression is made from the printing device and the same would occur if a long bell plug was provided, for if a long bell plug is used the plate 53 moves into the position X and as no plate is secured to the arm 54 at this position an impression is made from the printing device and as the position X is aligned with the position S the signal is operated. If it is desired to operate the signal under this condition of operation when a printing device is skipped, a plate 57' is secured to the arm 54 and this plate 57' is spaced from the plate 57 as the plate 56 is spaced from the plate 58 and the plate 57' is located at the position X in Fig. 5a. Thus when a plate 57' is provided, the platen is held against a printing operation and the signal is operated.

The block 66 is fast on an arm 65 fast on the shaft 64 journaled in the frame adjacent the shaft 37 and each time the block 66 is engaged by the foot member 61, the shaft 64 is turned. Fast on the shaft 64 is an arm 67 having a notch 68 therein normally engaging the ledge 69 on the bell crank 70, said notch and ledge being held in engagement by the spring 71. When, however, the shaft 64 is pivoted, the notch 68 is disengaged from the ledge 69 and the spring 72 pivots the bell crank 70 about the pivotal mounting 73 thereof on the casting 131 to rapidly move the knocker 74, carried by the bell crank, into engagement with the bell 75 mounted on the casting 131 to thereby produce an audible signal. In order to reposition the parts after such operation and when the foot portion 61 has moved upwardly on the next operation of the machine and disengaged the block 66, a collar 76 is fast on the shaft 37 and carries a pin 77 engageable with the end of the arm 78 of the bell crank 70 and when this pin engages the end of this arm the parts are moved into the position illustrated in Fig. 3, the ledge 69 engaging the upper part of the arm 67 to limit the action of the spring 71 until the parts are so repositioned.

It has been pointed out that the selecting mechanism of the invention may be used to not only control the platen but also other portions of the machine. For example, if a numbering device is used it is desirable that this be rendered inoperative when a printing device is skipped in order that the numbering device will not be advanced. Such an arrangement is shown in the previously referred to Colyer application, and as set forth therein the numbering device is operable from a shaft 213 having a shouldered dog 214 thereon engageable by one end of a link 217 to which a reciprocatory movement is imparted. In this link 217 there is a slot 222 through which a pin 223 is extended, said pin also being extended through the bifurcated boss 221, in the bifurcation of which the link 217 is rested. The boss 221 is carried by the arm 220 of the bell crank 218 and when the spring-pressed plunger 225 is actuated in the previously described manner, movement is imparted to the bell crank 218 whereby the boss 221 is moved upwardly to disengage the end of the link 217 from the shouldered dog 214. Thus, when reciprocatory movement is imparted to the link 217 no movement will be imparted to the dog 214 and consequently the shaft 213 and thus the numbering device will not be advanced. Manifestly, an arrangement similar to this might be provided for rendering any desired portion of the mechanism inoperative and such is intended to be within the spirit and scope of my invention.

In the foregoing description I have set forth a selecting mechanism which may be expeditiously set up to perform only a determined selection. The determination of the selection is regulated by a removable member which may be formed in a desired manner and by providing removable members or matrices having different characteristics various selections may be attained. The detecting portions of the selecting mechanism are movable with parts of the printing device feeding mechanism and therefore properly timed operation of these detecting portions is assured. Moreover, the detecting portions may be set in a definite manner by cooperating with a lacuna provided on the printing devices and in order to accomplish this the detecting portions are separated from the part of the selector which is positioned by the setting thereof and this separation of the detecting portions from this part is brought about by a device operable in definite timed relation with the movement of the detecting portions into detecting position. Furthermore, the arrangement is one wherein a certain definite selection may be performed and yet by making a simple change in the mechanism a directly opposite manner of operation may be attained, thus affording a reversal of operation of the machine. In addition to this the selecting mechanism is one which may be expeditiously employed to control different mechanisms in the machine and if desired this selecting mechanism might be arranged to interrupt the entire operation of the machine by disengaging the main clutch should this be desired. Moreover, since the detecting portions engage the lacuna at right angles thereto, I have provided means for preventing displacement of the lacuna and the printing device when engaged by these detecting portions which further insures proper operation of the device.

In the foregoing description I have illustrated and described a selected embodiment of my invention but it is to be understood that this is capable of variation and modification and I there-

fore do not wish to be limited to the precise details set forth but desire to avail myself of such changes and alterations as fall within the purview of the following claims:

5. I claim:
1. In a printing machine, a platen device movable between operative and inoperative positions, means sequentially feeding printing devices through the machine, a selecting mechanism, a holding member engageable with said platen device to hold said platen device in inoperative position, and means operated by said selecting mechanism for moving the holding member into holding position.
  2. In a printing machine, a platen device movable between operative and inoperative positions, means sequentially feeding printing devices through the machine, a selecting mechanism, a holding member engageable with said platen device to hold the platen device in inoperative position, yieldable means normally holding the holding member out of holding position, and means operated by the selecting mechanism for moving the holding member into holding position against the action of said yieldable means.
  3. In a machine of the class described, means feeding variable devices through the machine, said devices having identifying means thereon, a selecting mechanism, a movable member adapted for operation on said devices, holding means engageable with said movable member, and means for moving said holding means into engagement with said movable member, said selecting mechanism being operable to motivate the moving means to move the holding means into engagement with the movable member when said selecting mechanism cooperates with the identifying means on said devices in a predetermined manner.
  4. In a machine of the class described, means feeding variable devices through the machine, said devices having identifying means thereon, a selecting mechanism, a movable member adapted for operation on said devices, holding means engageable with said movable member, means for moving said holding means into engagement with said movable member, and a removable member mounted in said selecting mechanism and adapted to control the operation thereof, said selecting mechanism being operable to motivate the moving means to move said holding means into engagement with said movable member when said selecting mechanism cooperates with identifying means on said devices in a manner determined by said removable member.
  5. In a printing machine, a platen, means sequentially moving printing devices through printing position in the machine, means holding said platen in an upper inoperative position and adapted to be withdrawn to permit said platen to be moved into printing position and operable to impart printing impetus to said platen upon movement of the platen into printing relation with a printing device in printing position, holding means, means for operating said holding means to retain said platen in the upper inoperative position upon withdrawal of the means holding said platen in said position whereby said platen is prevented from moving into printing position and printing impetus is not imparted thereto, and selector means cooperating with the printing devices and determining the operation of the means for operating the holding means.
  6. In a printing machine, a platen, means sequentially moving printing devices through
  - printing position in the machine, means holding said platen in an upper inoperative position and adapted to be withdrawn to permit said platen to be moved into printing position and operable to impart printing impetus to said platen upon movement of the platen into printing relation with a printing device in printing position, holding means, means for operating said holding means to retain said platen in the upper inoperative position upon withdrawal of the means holding said platen in said position whereby said platen is prevented from moving into printing position and printing impetus is not imparted thereto, and a selecting mechanism for controlling the means operating said holding means whereby the operation of said holding means may be selectively controlled.
  7. In a printing machine, a platen, means holding said platen in an upper inoperative position, means for withdrawing said holding means, means imparting printing impetus to said platen immediately prior to movement thereof into operating position, a selecting mechanism, and normally inoperative means operable by said selecting mechanism when it is operated in a predetermined manner for holding said platen in said upper inoperative position after said holding means is withdrawn to thereby prevent the imparting of printing impetus to said platen.
  8. In a printing machine, means sequentially moving printing devices having identifying means thereon through the machine, a platen, means normally holding said platen in an upper inoperative position, means for withdrawing said holding means, a selecting mechanism adapted to cooperate with the identifying means on said printing devices, and normally inoperative means movable into engagement with said platen to prevent movement thereof after said holding means is withdrawn when said selecting mechanism cooperates with predetermined identifying means on said printing devices.
  9. In a printing machine, means sequentially moving printing devices having identifying means thereon through the machine, a platen, means normally holding said platen in an upper inoperative position, means for withdrawing said holding means, a selecting mechanism adapted to cooperate with the identifying means on the printing devices, a member insertable into said selecting mechanism for determining operation thereof when moved into cooperation with said identifying means, normally inoperative means operable by said selecting mechanism and operable in accordance with the operation of said selecting mechanism as determined by said insertable member and engageable with said platen to hold the same against movement after said holding means is withdrawn when said selecting means cooperates with predetermined identifying means on the printing devices.
  10. In a printing machine, means sequentially moving printing devices having identifying means thereon through the machine, a platen, means normally holding said platen in an upper inoperative position, means for withdrawing said holding means, means imparting printing impetus to said platen after it has moved following the withdrawal of said holding means, a selecting mechanism, a removable part adapted to be positioned in said selecting mechanism to determine operation thereof when moved into cooperation with the identifying means on said printing devices, and normally inoperative means operable when said selecting mechanism cooperates with predetermined identifying means on said printing devices.

ates with determined identifying means on said printing devices and movable to hold said platen against movement upon withdrawal of said holding means.

- 5 11. In a printing machine, means sequentially moving printing devices through the machine and including an operative part, a selector mechanism carried by said operative part, means in the machine controlled by said selector mechanism, and operating means for operating said moving means and the operative part thereof to move said selector mechanism into cooperation with said printing devices.
- 10 12. In a printing machine, means sequentially moving printing devices having identifying means thereon through the machine and including an operative part, a selector mechanism carried by said operative part and including detecting portions, means in the machine controlled by said selector mechanism, and operating means for operating said moving means and the operative part thereof to bodily move said selector mechanism to move the detecting portions thereof into cooperation with the identifying means

- 15 13. In a printing machine, means sequentially moving printing devices having identifying means thereon through the machine and including an operative part, a selector mechanism carried by said operative part and including detecting portions and a positionable part, means in the machine controlled by said selector mechanism, and operating means for operating said moving means and the operative part thereof to bodily move said selector mechanism to move the detecting portions thereof into cooperation with the identifying means
- 20 14. In a printing machine, means sequentially moving printing devices having identifying means thereon through the machine and including an operative part, a selector mechanism carried by said operative part and including detecting portions and a positionable part, means in the machine controlled by said selector mechanism, and operating means for operating said moving means and the operative part thereof to bodily move the selector mechanism to move the detecting portions thereof into cooperation with the identifying means

- 25 15. In a printing machine, means sequentially moving printing devices having identifying means thereon through the machine and including an operative part, a selector mechanism carried by said operative part and including detecting portions and a positionable part, means in the machine controlled by said selector mechanism, and operating means for operating said moving means and the operative part thereof to bodily move the selector mechanism to move the detecting portions thereof into cooperation with the identifying means on the printing devices to determine the setup of said positionable part.

- 30 16. In a printing machine, means sequentially moving printing devices having identifying means thereon through the machine and including an operative part, a selector mechanism carried by said operative part and including detecting portions and a positionable part, means in the machine controlled by said selector mechanism, and operating means for operating said moving means and the operative part thereof to bodily move the selector mechanism to move the detecting portions thereof into cooperation with the identifying means on the printing devices to determine the setup of said positionable part, and means for separating said detecting portions from said positionable part when said detecting portions cooperate with said identifying means to be positioned in accordance with the identifying means and adapted to effect reengagement of said detecting portions and said positionable part to determine the setup of said selector and the operation of the means controlled thereby.

- 35 17. In a printing machine, means sequentially moving printing devices having identifying means thereon through the machine and including an operative part, a selector mechanism carried by said operative part and including detecting portions and a positionable part, means in the machine controlled by said selector mechanism, and operating means for operating said moving means and the operative part thereof to bodily move the selector mechanism to move the detecting portions thereof into cooperation with the identifying means on the printing devices to determine the setup of said positionable part, and said selector mechanism including a removable part embodying means for determin-

ing the cooperation between said detecting portions and said positionable part.

18. In a printing machine, means sequentially moving printing devices having identifying means thereon through the machine and including an operative part, a selector mechanism carried by said operative part and including detecting portions and a positionable part, means in the machine controlled by said selector mechanism, operating means for operating said moving means and the operative part thereof to bodily move the selector mechanism to move the detecting portions thereon into cooperating relation with the identifying means on the printing devices to determine the setup of said positionable part, means operated by said operating means for separating said detecting portions from said positionable part when said detecting portions cooperate with said identifying means to be positioned in accordance with the identifying means and adapted to effect reengagement of said detecting portions and said positionable part to determine the setup of said selector and the operation of the means controlled thereby, and said selector mechanism including a removable part embodying means for determining the setup of said positionable part upon engagement thereof with the detecting portions subsequent to the cooperation of said detecting portions with said identifying means.

19. In a printing machine, an operative device, means sequentially moving printing devices having identifying means thereon through the machine and including an operating means, a selecting mechanism, means for moving said selecting mechanism toward and away from the printing devices whereby the detecting portions of the selecting mechanism may be moved into cooperative relation with the identifying means on the printing devices, said moving means for said selecting mechanism being operated by said operating means, means separating operative portions of said selecting mechanism upon movement thereof to move the detecting portions thereof into cooperative relation with the identifying means on the printing devices and adapted to effect reengagement of said operative portions subsequent to cooperation of the detecting portions with the identifying means, and means controlled by said selecting mechanism and adapted to be operated subsequent to reengagement of the operative portions of said selecting mechanism to control the operation of said operative device.

20 21. In a printing machine, an operative device, means sequentially moving printing devices having identifying means thereon through the machine and including an operating means, a selecting mechanism, means for moving said selecting mechanism toward and away from the printing devices whereby the detecting portions of the selecting mechanism may be moved into cooperative relation with identifying means on the printing devices, said moving means for said selecting mechanism being operated by said operating means, means separating operative portions of said selecting mechanism upon movement thereof to move the detecting portions thereof into cooperative relation with the identifying means on the printing devices and adapted to effect reengagement of said cooperative portions subsequent to cooperation of the detecting portions with the identifying means to thereby position the control part of said selector, means operating the separating means from said operat-

- ing means, and means cooperating with the control part of said selector and adapted to be regulated thereby subsequent to the reengagement of the operative portions of said selecting mechanism to control the operation of said operative device.
19. In a printing machine, a platen, means sequentially moving printing devices through the machine and including a vertically movable member, a selecting mechanism embodying detecting members adapted to cooperate with identifying means on the printing devices, said selecting mechanism being connected to said vertically movable member to move therewith to engage and disengage the detecting members with the identifying means, and means controlled by said selecting mechanism for regulating operation of said platen as determined by the cooperation of said detecting members with said identifying means.
20. In a printing machine, a platen, means sequentially moving printing devices through the machine and including a vertically movable member, a selecting mechanism embodying detecting members adapted to cooperate with identifying means on the printing devices, said selecting means being connected to said vertically movable member to move therewith to engage and disengage the detecting members with the identifying means, a removable part for determining the operation of said selecting mechanism as regulated by the cooperation of said detecting members with said identifying means, and means controlled by said selecting mechanism for regulating operation of said platen as determined by said removable part.
21. A selector adapted for cooperation with control means including spaced members, means carrying the detecting and settable portions of said selector, and a mechanism for moving one of said means relative to the other of said means whereby the detecting portions of the selector may engage or pass between the spaced members, the engagement of the detecting portions with the spaced members or the passage of the detecting portions between the spaced members setting up the detecting portions in varied positions to thereby determine the setup of the settable portions of the selector.
22. A selector adapted for cooperation with control means including spaced members, means carrying the detecting and settable portions of said selector, and means for moving the carrying means toward the control means whereby the detecting portions of the selector may engage or pass between the spaced members, the engagement of the detecting portions with the spaced members or the passage of the detecting portions between the spaced members setting up the detecting portions in varied positions to thereby determine the setup of the settable portions of the selector.
23. In a printing machine, an operative device, means sequentially moving printing devices having identifying means thereon through the machine, a bodily movable selecting mechanism including a positionable part, means for freeing said positionable part to permit positioning thereof, means for moving the selecting mechanism toward and away from the printing devices to position said positionable part by the cooperation of the selecting mechanism with the identifying means on the printing devices, and control means having parts thereon adapted for cooperation with said positionable part and adapted to control the operation of said operative device.
24. In a printing machine, an operative device, means sequentially moving printing devices having identifying means thereon through selecting and printing positions in the machine, a selecting mechanism including a positionable part, means for freeing said positionable part to permit positioning thereof, moving means for moving the selecting mechanism toward the printing device in selecting position whereby said positionable part is arranged in a position determined by the cooperation of said selecting mechanism with the identifying means on the printing device in selecting position, and control means including parts adapted for cooperation with said positionable part and adapted to regulate the operation of said operative device, said moving means moving said selecting mechanism away from the printing device in selecting position and toward said control means after the positioning of said positionable part.
25. In a printing machine, an operative device, means sequentially moving printing devices having identifying means thereon through selecting and printing positions in the machine, a selecting mechanism including a positionable part, means for freeing said positionable part to permit positioning thereof, moving means for moving the selecting mechanism toward the printing device in selecting position whereby said positionable part is arranged in a position determined by the cooperation of said selecting mechanism with the identifying means on the printing device in selecting position, control means including spaced parts arranged in groups, and means affording adjustment of the positionable part and the groups of parts on said control means whereby said positionable part cooperates with but one of the groups of parts on said control means, said moving means moving said selecting mechanism away from the printing device in selecting position and toward said control means after the positioning of said positionable part.
26. In a printing machine, an operative device, means sequentially moving printing devices having identifying means thereon through selecting and printing positions in the machine, a selecting mechanism including a positionable part, means for freeing said positionable part to permit positioning thereof, means for locating said positionable part in alternate operative positions, means for moving the selecting mechanism toward the printing device in selecting position whereby said positionable part is arranged in a determined position by the cooperation of said selecting mechanism with the identifying means on the printing device in selecting position, and control means including control members arranged in groups, said groups being aligned with the alternate positions of said positionable part, said moving means moving said selecting mechanism away from the printing device in selecting position and toward the control means after the positioning of said positionable part by said selecting mechanism to thereby control the operation of said operative device.
27. A selecting mechanism including a bracket supporting a plurality of detecting members, a head, a removable part mounted in said head for regulating the relative position of said detecting members and said head, means for freeing the detecting members from said head, an arm mounted on said bracket, means connecting said arm and said head to move as a unit, a device having

a plurality of parts thereon adapted for cooperation with said arm, and means for moving said bracket to move said detecting members into detecting position when the detecting members are freed from said head to position said head and arm upon subsequent cooperation of the detecting members and head and for subsequently moving said bracket to move said arm toward said device to thereby position said arm relative to the parts on said device to thereby determine the operation of means controlled by said selecting mechanism.

28. A selecting mechanism including a bracket supporting a plurality of detecting members, a head, a removable part mounted in said head for regulating the relative position of said detecting members and said head, means for freeing the detecting members from said head, an arm, means for mounting said arm in selected positions on said bracket, means connecting said arm and said head to move as a unit, a device having a plurality of parts thereon adapted for cooperation with said arm, and means for moving said bracket to move said detecting members into detecting position when the detecting members are freed from said head to position said head and arm upon subsequent cooperation of the detecting members and head and for subsequently moving said bracket to move said arm toward said device to thereby position said arm relative to the parts on said device to thereby determine the operation of the means controlled by said selecting mechanism.

29. In a printing machine, a platen, means sequentially moving printing devices having identifying means thereon through the machine, a drive shaft, a driven shaft operable in timed relation with said drive shaft, means operable with said drive shaft for operating said platen, a selecting mechanism operable with said printing device moving means, a removable part for determining operation of said selecting mechanism, normally inoperative means, and means carried by said selector and engageable with a part of said normally inoperative means when located in certain positions determined by said removable part to operate another part of said normally inoperative means to hold said platen against operation.

30. In a printing machine, a platen, means sequentially moving printing devices having identifying means thereon through the machine, a drive shaft, a driven shaft operable in timed relation with said drive shaft, means operable with said drive shaft for operating said platen, a selecting mechanism operable with said print-

ing device moving means, a removable part for determining operation of said selecting mechanism, normally inoperative means, means carried by said selector and engageable with a part of said normally inoperative means when located in certain positions determined by said removable part to operate another part of said normally inoperative means to hold said platen against operation, and a signal device operable by the means carried by said selector when said means is disposed in certain positions as determined by said removable part.

31. In a printing machine, a platen, means sequentially moving printing devices having identifying means thereon through the machine, a drive shaft, a driven shaft operable in timed relation with said drive shaft, means operable with said drive shaft for operating said platen, a selecting mechanism operable with said printing device moving means, a removable part for determining operation of said selecting mechanism, normally inoperative means, means carried by said selector and engageable with a part of said normally inoperative means when located in certain positions determined by said removable part to operate another part of said normally inoperative means to hold said platen against operation, a signal device operable by the means carried by said selector when said means is disposed in certain positions as determined by said removable part to operate another part of said normally inoperative means to hold said platen against operation, and a signal device operable by the means carried by said selector when said means is disposed in certain positions as determined by said removable part to operate another part of said normally inoperative means to hold said platen against operation.

32. In a printing machine, a platen, means sequentially moving printing devices having identifying means thereon through the machine, a drive shaft, a driven shaft operable in timed relation with said drive shaft, a bracket supporting a plurality of detecting members, a head, means for moving said head and bracket toward and from the printing devices, a removable part mounted in said head for regulating the relative position of said detecting members and said head, and means operable with said driven shaft for separating said head from said detecting members as said detecting members are engaged with said identifying means whereby said removable part determines the relative position of said head and said detecting members as said head again moves toward said detecting members, an arm positioned by said head, and a member including portions engageable by said arm when said arm is located in certain positions and said bracket is moved toward said arm.
